UNITED STATES PATENT OFFICE.

EDWARD O. CROSS, OF FOSTORIA, OHIO, ASSIGNOR TO THE FOSTORIA GLASS SPECIALTY COMPANY, OF FOSTORIA, OHIO, A CORPORATION OF OHIO.

DESIGN FOR A GLOBE FOR PENDANT LIGHTS.

No. 39,405.

Specification for Design.

Patented July 7, 1908.

Application filed April 4, 1908. Serial No. 425,282. Term of patent 7 years.

To all whom it may concern:

Be it known that I, EDWARD O. CROSS, a citizen of the United States, residing at Fostoria, in the county of Seneca and State of Ohio, have invented a new, original, and ornamental Design in Globes for Pendant Lights, of which the following is a specification, reference being had to the accompanying drawing, forming a part thereof.

Figure 1 is an elevation of said globe, and Fig. 2 is a perspective view thereof.

I claim:

The ornamental design for a globe for pendant lights, substantially as shown.

EDWARD O. CROSS.
